UNITED STATES PATENT OFFICE.

LYNN G. RILEY, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,336,583.

Specification of Letters Patent. Patented Apr. 13, 1920.

Application filed October 6, 1915. Serial No. 54,342.

To all whom it may concern:

Be it known that I, LYNN G. RILEY, a citizen of the United States, and a resident of Wilkinsburg, in the county of Allegheny and State of Pennsylvania, have invented a new and useful Improvement in Control Apparatus, of which the following is a specification.

My invention relates to control apparatus, and it has special reference to controllers of the drum type that are adapted for governing electric railway motors and the like.

The object of my invention is to provide a relatively simple and inexpensive device of the above-indicated character which shall be adapted to increase the speed of contact-making and breaking within the controller, whereby the formation of destructive arcs, welding of contact surfaces and other injurious conditions may be obviated.

More specifically stated, it is the object of my invention to provide, in connection with a controller of the drum type, a position-accentuating means of the usual type which shall be adapted to actuate the control fingers toward and away from the co-operating contact segments of the controller under predetermined conditions.

It is well known to those skilled in the art that the amount of destructive arcing which takes place when a circuit is made or broken within a controller varies in an inverse ratio to the relative speed of the co-operating contact members at the instant that the circuit is made or broken. In many prior controllers of the type wherein the contact segment is rotated and the co-operating control fingers remain stationary, the relatively low speed of contact-making has, in some cases, effected a welding of the parts by reason of the high resistance of the initial line contact before complete contact is established. Moreover, when the circuit has been broken, injurious arcs have been created, which has resulted in the burning and pitting of the contact members.

According to my present invention, I provide means for obviating the above-mentioned difficulties by materially increasing the relative speed of contact-making and breaking of control fingers and contact segments within controllers of the drum type. To effect the desired result, the finger-base

for supporting the control fingers is mov- 55
ably mounted upon the control drum proper, and the pawl that comprises, together with a suitable star-wheel, the customary position-accentuating means for the control drum, is mechanically associated with the 60 finger-base to effect movement thereof toward and away from the control drum when the drum is operated out of and into its "off" position, respectively, thereby greatly increasing the relative approaching and re- 65 ceding speeds of the control fingers and contact segments, as hereinafter more fully described.

In the accompanying drawing, Figure 1 is a view in transverse section taken along 70 the line I—I of Fig. 2, which is a view in elevation of a portion of a drum-controlling device constructed in accordance with my invention, the cover being removed.

Referring to the drawing, the structure 75 shown comprises a suitable incasing member or cover 1 which is associated with a suitable back-plate 1^a, in accordance with customary practice; a switching device, here shown as a control drum CD of a familiar 80 type, that is located within the cover 1; a finger-base FB that is associated with the control drum CD in a manner to be described; and position-accentuating means PA for the control drum CD. 85

The control drum CD is provided with a centrally located shaft 2 that has its lower end supported within a suitable bearing block 3, the upper end of the shaft extending through an appropriate bearing bushing 4 within the incasing member 1; and a familiar handle member 5 is associated with the upper end of the shaft 2 outside of the cover 1. Interconnected contact segments 6, of a contour suitable for the purpose intended, are associated with the shaft 2 of the control drum in any appropriate manner and are adapted to rotatively engage a plurality of suitable control fingers F that are mounted upon the finger board FB, in 95 accordance with a familiar practice, and are respectively connected to conductors C to complete the desired circuit connections. The finger board FB is here shown as being trapezoidal in section, and a plurality 100 of suitable bracket members or arms 7 and 8 are respectively secured to the ends of the finger-board by means of suitable screws

9 or their equivalent, the arms 7 and 8 being provided with apertured ends through which the shaft 2 loosely extends. The finger board FB is thus rotatively mounted upon the control drum CD for a purpose to be set forth later.

5 The position-accentuating means PA comprises a star-wheel 10, of a familiar form, that is rigidly associated with the shaft 2 intermediate the bearing block 3 and the bracket member 8, and a pawl member 11 that is adapted to engage the notched periphery of the star-wheel. Notches 12, 13, 14, 15, etc., are provided in the outer edge 10 of the star-wheel 10 to respectively correspond to the control positions of the drum, as will be understood, the end notch 12 that corresponds to the "off" position of the controller being deeper than any of the other notches, for a purpose to be explained.

20 The pawl member 11 is provided with an intermediate outwardly extending arm 16 that is disposed slightly above the plane of the remainder of the pawl member, as best shown in Fig. 2, and the pawl member, as a whole, is pivoted at a point 17 opposite the arm 16, upon a suitable pedestal or block 18 that is suitably associated with the base 1^b of the controller. A suitable roller 19 is associated with one end of the pawl member 11 to engage the notches of the star-wheel, in accordance with customary practice, and a suitable helical spring 20 is disposed intermediate the other end 21 of the pawl member and a point 22 of the back-plate 1^a to bias the roller 19 to engagement with the various notches, as will be understood.

40 To effect movement of the finger base FB through the agency of the position-accentuating means PA, the arm 16 is provided, near its outer end, with a suitable pin or stud 23, the free end of which is located within a slot or opening 24 of the bracket member 8, whereby a suitable pin-and-slot connection is established intermediate the pawl member 11 and the finger base FB. However, it will be understood that any other suitable mechanical connection between the two parts just mentioned may be employed, if desired.

45 Although, for the sake of simplicity and clearness, I have omitted from the drawing the customarily employed reversing switch and other associated structural details which are not material to my present invention, it will be appreciated that such apparatus is normally employed in connection with my invention.

60 Assuming the parts to occupy the positions shown, the operation of the apparatus may be set forth as follows: Upon movement of the control drum CD in a clockwise direction by means of the handle member 5, as indicated by the arrow, the star-wheel

10 gradually forces the roller 19 out of the initial or "off"-position notch 12 along that portion of the surface of the star-wheel which lies intermediate the notches 12 and 13. The pawl member 11 is thus actuated 70 around the pivotal point 17 in a counter-clock-wise direction, whereby the pin 23 engages one side of the slot 24 and effects rotative movement of the finger-board FB and the associated control fingers F toward the 75 approaching contact segment 6 of the control drum. In this way, the speed of contact-making within the controller attains a relatively rapid rate, and all danger of welding of the control fingers and contact 80 segments is obviated. The arrangement of parts is such that the roller 19 just passes the crest of the surface lying intermediate the notches 12 and 13 when contact is established between the control fingers and the 85 contact segments.

85 The pawl member 11 then rotates through a relatively small angle in the clock-wise direction as the notch 13 approaches the roller 19. However, by reason of the arrangement of parts and the difference in the operating radii of the roller 19 and the finger base FB, the control fingers F drop back at a speed somewhat less than the velocity of the drum as the roller 19 approaches 95 the notch 13, so that contact is still maintained. Inasmuch as the initial notch 12 is deeper than the succeeding notches, the movement of the pawl member 11 and the finger-base FB, during the remainder of 100 the forward operation of the control drum, is relatively slight, as will be understood.

90 In other words, the pawl member 11 oscillates around the pivotal point 17, while the finger base FB and, therefore, the fingers 105 F have a motion of pure rotation around the drum shaft 2. Consequently, the actual contact between the fingers F and the drum segment 6 is not affected by movement of the roller 19 into successive notches 13, 14, 110 etc.

115 When the control drum is returned toward its off position, so that the roller 19 gradually drops into the relatively deep notch 12, the pawl member 11 is rotated through a relatively large angle in a clockwise direction, whereby the pin-and-slot connection between the pawl member and the finger-base causes the control fingers F to move away from the receding contact 120 segment 6, and the speed of separation of the coöperating contact members, as the drum reaches its off position, is relatively great, thus preventing the formation of the destructive arcs hereinbefore referred to. 125

I do not wish to be restricted to the specific structural details or arrangement and location of parts herein set forth, as various modifications thereof may be effected without departing from the spirit and scope 130

of my invention. I desire, therefore, that only such limitations shall be imposed as are indicated in the appended claims.

I claim as my invention:

5 1. In a switching device, the combination with a control finger and a coöperating contact segment, of a supporting frame, a movable carrying member and position-accentuating means for said segment mounted 10 on said frame, means for movably mounting said finger on said carrying member, and means associated with said position-accentuating means for actuating said finger under predetermined conditions.

15 2. In a switching device, the combination with a control finger and a coöperating contact segment, of position-accentuating means for said segment, and means dependent upon the movement of said position-accentuating 20 means for actuating said finger toward and away from said segment under predetermined conditions and for maintaining contact between said finger and said segment during the movement of said position-ac- 25 centuating device.

3. In a switching device, the combination with a plurality of control fingers, a control drum and a coöperating contact segment disposed thereon, of position-accentuating 30 means for said drum, means for rotatably mounting said fingers on said drum, and means interposed between said position-ac- centuating means and said mounting means for actuating said fingers respectively to- 35 ward and away from said segment upon predetermined forward and backward move- ment of the segment.

4. In a switching device, the combination with a plurality of control fingers, a control 40 drum and a coöperating contact segment disposed thereon, of means for rotatably mounting said fingers on said drum, a notched member movable with said drum, a pawl adapted to engage the notched mem- 45 ber, and means associated with said pawl for actuating said fingers under predeter- mined conditions.

5. In a switching device, the combination with a plurality of control fingers, a control 50 drum, and a coöperating contact segment disposed thereon, of means for rotatably mounting said fingers on said drum, a notched member movable with said drum, a pawl adapted to engage the notched mem- 55 ber, and means dependent upon the move- ment of said pawl for actuating said fingers toward and away from said segment under predetermined conditions.

6. In a switching device, the combination 60 with a plurality of control fingers, a control drum, and a coöperating contact segment disposed thereon, of means for rotatably mounting said fingers on said drum, a notched member movable with said drum, a 65 pawl adapted to engage the notched mem-

ber, and means associated with said pawl for increasing the speed of contact-making and breaking of said finger.

7. In a switching device, the combination with a plurality of control fingers, a control drum, and a coöperating contact segment disposed thereon, of a notched member movable with said drum, a pawl adapted to engage the notched member, means for rotatably mounting said fingers on said drum, 70 and means interposed between said pawl and said mounting means for actuating said fingers respectively toward and away from said segment upon predetermined forward and backward movement of the segment. 80

8. In a controller, the combination with a plurality of control fingers, a control drum and a coöperating contact segment disposed thereon, of a star-wheel movable with said drum and having a plurality of notches re- 85 spectively corresponding to the several control drum positions, a pawl adapted to engage the notched member, a finger-base for said fingers rotatably mounted on said drum, and a mechanical connection between said pawl and said finger-base for actuating said fingers respectively toward and away from said segment upon movement of the pawl out of and into a predetermined notch of said star-wheel. 90

9. In a controller, the combination with a plurality of control fingers, a control drum and a coöperating contact segment disposed thereon, of a star-wheel movable with said drum and having a plurality of notches re- 100 spectively corresponding to the several control-drum positions, the notch correspond- ing to "off" position being deepest, a pawl adapted to engage the notched member, a finger-base for said fingers rotatively 105 mounted on said drum, and a mechanical connection between an arm of said pawl and said finger-base for actuating said fingers respectively toward and away from said seg- 110 ment upon movement of the pawl out of and into said "off"-position notch to increase the speed of contact-making and breaking of said control fingers.

10. In a controller, the combination with a stationary supporting member, a plurality 115 of control fingers, a control drum and a co- operating contact segment disposed thereon, of a star-wheel movable with said drum and having a plurality of notches respectively corresponding to the several control drum 120 positions, the notch corresponding to "off" position being deepest, a pawl having a roller disposed near one end to engage said star- wheel and also having an outwardly-project- ing arm, a biasing spring secured to the op- 125 posite end of the pawl, means for pivotally mounting said pawl near said supporting member at a point opposite said arm, a finger-base for said fingers rotatively mounted on the control drum, and a mechanical con- 130

nection between said pawl arm and said finger-base for imparting a rotative movement to said finger-base respectively toward and away from said contact segment upon movement of the pawl out of and into said "off" position notch, whereby the speed of contact-making and breaking of said fingers is increased.

11. In a controller, the combination with 10 a control finger and a coöperating contact segment, of position-accentuating means and a movable carrying member for said segment, means for movably mounting said finger on said carrying member, and a mechanical connection between said means and said control finger for actuating the finger toward the approaching segment when contact is to be made and away from the receding segment when contact is to be broken, where- 20 by the speed of contact-making and breaking of the control finger is increased.

12. In a controller, the combination with a plurality of control fingers, a control drum and a contact segment mounted thereon, of 25 a star-wheel movable with said drum and having a plurality of notches respectively corresponding to control-drum positions, a pawl adapted to engage said star-wheel, a finger-base for said fingers rotatably mounted on said drum, and means interposed be- 30 tween said pawl and said finger-base for actuating the fingers toward the approach-

ing segment upon movement of the pawl out of the notch corresponding to the drum "off" position and for actuating the fingers away 35 from the receding segment upon the return of the pawl to said notch.

13. In a switching device, the combination with a contact segment and a coöperating contact finger disengaged therefrom when 40 said segment and said finger occupy a normal position, of accentuating means for said segment which is adapted to actuate said finger toward said segment when said segment is moved from said normal position. 45

14. In a switching device, the combination with a control finger and a coöperating contact segment, of an accentuating cam having a recess, a pawl for coöperating with said recess, and means for actuating said 50 finger toward said segment when said pawl is moved from said recess.

15. In a controller, the combination with a control drum and a coöperating contact finger rotatably mounted thereon, of a 55 notched member movable with said drum, and a pawl adapted to engage said notched member and having an outwardly extending arm loosely connected to said finger.

In testimony whereof, I have hereunto 60 subscribed my name this 28th day of Sept., 1915.

LYNN G. RILEY.
